HORATIO S. TITTLE, OF SAN FRANCISCO, CALIFORNIA.

OSCILLATING SAFETY-SWITCH.

1,278,522.

Specification of Letters Patent. Patented Sept. 10, 1918.

Application filed November 16, 1916. Serial No. 131,776.

To all whom it may concern:

Be it known that I, HORATIO S. TITTLE, citizen of the United States, residing at 243 Minna street, San Francisco, in the county 5 of San Francisco, State of California, have invented a new and useful Oscillating Safety-Switch, of which the following is a specification, in such full and clear terms as will enable those skilled in the art to construct and use the same.

This invention relates to an oscillating safety switch for use in starting motors where a very heavy starting current is required, and after which the switch is placed 10 in a different position called the running position, in which the current passes through suitable fuses to prevent the motor or other electrical apparatus from being too heavily overloaded. It will be understood by those skilled in the art that motors and other electrical apparatus must frequently take very heavy overloads for short periods of time, and in order to protect the apparatus, fuses must be provided which will not continuously 15 take such heavy overloads as are momentarily required, and it therefore becomes necessary to provide means whereby the motor or other apparatus will have current delivered to it directly from the line during 20 the period it is to receive such overload, and after which the switch is turned to the running position and current is delivered to the apparatus through suitable fuses, which will adequately protect the apparatus.

Another object of the invention is to provide a barrier between the several switch points whereby the danger of arcing is reduced to a minimum and whereby the size 25 of the switch may be reduced.

Another object of the invention is to provide a protection for the switch which will prevent it from being tampered with unless the person seeking to operate it or to repair it first releases the switch points from the 30 running position.

Another object of the invention is to provide a no voltage release mechanism which will operate to release the switch if the voltage goes off the line.

Other objects of the invention will appear 35 as the description proceeds.

An embodiment of the invention is shown in the drawings in which the same reference numeral is applied to the same portion 40 throughout, but I am aware that there may be many modifications thereof.

Figure 1 is a vertical sectional view of the machine.

Fig. 2 is a plan view of the machine.

Fig. 2^a is a side elevation of the key. 60

Fig. 3 is a detailed view showing the switch lever locking mechanism.

Fig. 4 is a side elevation of the complete machine.

Fig. 5 is a side elevation of one of the 65 frames.

Fig. 6 is a vertical sectional view through the switch blade holding cylinder, and

Fig. 7 is a detailed view of one of the fiber 70 blocks holding the contact points.

The numeral 1 indicates a suitable box having sides 2, 3, 4 and 5 with a cover which is hinged to the side 4. The switch comprises two frames 7 and 8 which have inwardly projecting slotted lugs 9 and 10 for 75 securing the fuse block 11 in place, said fuse block carrying a fuse for each of the wires connecting with the electrical apparatus, in the present instance three wires being used, and the fuse block having a fuse 80 for each of them. The frames each consist of a base member 12, upright post 13, 2 inclined posts 14, 15, to which are respectively connected two oppositely inclined posts 16 and 17, which carry horizontal bars 18, 19, 85 extending from each other, and which are connected to a vertical post 20 split to provide two bars 21, 22, so that oscillating switch blade carrying mechanism can be placed in position from the top after being 90 completely assembled. The two frames 7 and 8 have their members 14 to 17 inclusive connected together by means of four asbestos fiber or other insulating material bars 23, 95 said bars being connected with the frame by means of suitable screws, the present switch being intended to handle three wire circuits as each of its bars is notched to receive the spring contact points 27, 28, 29, which contact points are secured thereto by means of 100 suitable screws through the fiber blocks, and there are two other notches in each block as indicated at 30, 31, to receive the barriers between the switch blades. Each of the frames 7 and 8 is provided with an outwardly extending flange at 32, which provide bearings for the stub shaft 33 and for the shaft 34, which shafts support the switch blades. Numerals 35, 36, 37 indicate the 105 switch blades which are in the form of flat 110 rectangular blades having a central opening. Each of the switch blades is supported

between a pair of blocks 38, 39, grooved as indicated at 40 to receive the switch blade and provided with three holes, 41, 42, 43. The holes 41, 43 receive bolts 44, 45, which pass through plates 46, 47, and through the several disks making up the switch blade carrying member, there being three disks 38, three of the disks 39 oppositely placed in pairs, and two guard disks or barrier disks 50, 51, 5 mounted on opposite sides of the knife blade 36, and between it and the adjacent switch blades 35, 37. A rod 52 of insulating material such as fiber or any other material of that character passes through the center of 10 the several disks and through a hole in each of the switch blades for the purpose of holding said switch blades in a fixed position with respect to the member carrying them. Bearing caps 53 hold the shafts 33, and 34 15 in their proper position and allow the knife carrying mechanism to oscillate sufficiently for the purpose to be presently explained. Mounted on the shafts 33, 34, are two short levers 55, 56, which are rigidly connected 20 with said shafts, and which have holes therein to receive hooks on the ends of the two spiral springs 57, 58. The spiral springs are connected at their upper ends to an outwardly turned hook 59 connected with a 25 plate 60, which is bolted to the top of the two frames, there being two of said spring holding horns oppositely placed. The shaft 34 is long enough to project through the side 4 of the inclosing casing, and it has a lever 30 61 connected therewith, which lever is used for the purpose of oscillating the switch blades from the starting position to the running position as may be desired. In order to secure the switch in the running 35 position, it is provided with a stiff spring 62 which is connected with the shaft 34 and extends along one side of the lever 61 and terminates in a handle 63, said handle being connected with the spring by means of the 40 bolt 64, which also extends through the lever 61, and is again connected with the spring 62 at 65. This spring affords means for stopping the lever 61 when the lever is rotated to the starting position by having said 45 spring come against the projecting stop 66 on the side 4 of the inclosing casing. In the running position the lever is turned down to the position shown in Fig. 1 and the spring 62 is then engaged with the swinging latch 67, which latch is pivoted to a 50 spring press stud 68 normally held in a position to disengage the latch from the spring by the spiral spring 69. At the lower end of the latch 67 there is a projecting lug 70 which engages an oppositely placed latch 71 on the upper end of the armature 72 passing into the coil 73, the 55 object of the following construction being to provide means whereby the latch 67 will be held in the position shown in Fig. 2 only 60 when current is passing through the coil 73, the weight of the armature at other times causing it to be disengaged from the latch. In order to secure the handle of the switch in the inoperative position, the box has a 70 projecting boss 74 with an opening therein to receive the end of a screw 75, and said screw may be operated only with a particular type of key. Since the switch is to be installed in a place where it cannot be tampered with by unauthorized persons, the box with the sides and top illustrated is made use of, and the top is provided with an L shaped arm 77 which bears upon one end of the pin 68 when the cover is closed, thereby holding the latch 67 in the proper position to hold the lever 61 with the switch blades engaged with the contact points for the running position through the fuse blocks. When the box is opened by the person in charge thereof, the act of opening it will release the latch 67 and thereby bring the switch blades to the neutral position. The electric supply cables are connected with the switch as illustrated in Fig. 4 in 80 which 80 indicates the supply wire, 81 the wire connecting one of the contact points on each insulating bar with a point on the next adjacent bar, 82 indicates a cable connecting one of the switch points on one of the 85 insulating bars with one end of the fuse block, 83 a cable connecting the other end of the fuse block with one of the contact points on the next adjacent lower bar, while a wire 84 connects the contact points on the lower bar with the apparatus to be operated. The operation of this switch is as follows:—Assuming a motor or other piece of electrical apparatus to be started by closing the switch, the operator first turns the handle to the 90 right, Fig. 4, only the contact blades of the movable member connecting the contact points A and B of the entire series, see Fig. 4. As soon as this contact has been made, current will be delivered to the apparatus being started from the main line 80 of the line 84 without the interposition of the fuses. As soon as the motor or other apparatus is started the switch lever will be pushed to the 95 left, Fig. 4, so that it is engaged by the latch 67 as illustrated in Fig. 2, whereupon the switch blades will connect the contact points C and D of the entire series, in which event current will be delivered from the feed wire 80 to the wires 84 after having passed through the connections in the fuse block, and so long as current remains on, the coil 73 will hold the lever in the engaged position, but as soon as the current goes off the latch 67 will be released and the lever 61 will 100 turn to the neutral position. It is to be noted that in the starting, the stop 66 determines the position to which the switch handle shall be turned, but does not provide means to hold it in that position, but as 105 110 115 120 125 130

soon as the motor has been started the operator can turn the switch handle to the position shown in Fig. 2 and can lock it in that position with the latch 67. When the switch 5 is not in use, it may be locked in the neutral position with the key 76 and lock 75.

Having thus described my invention what I claim as new and desire to secure by Letters Patent of the United States, is as follows:—

1. An electric switch comprising a plurality of pairs of contact points, a plurality of oscillating switch blades pivoted adjacent their centers adapted to connect the opposite pairs of contact points, and a barrier 15 between the several switch blades movable therewith.
2. An electric switch comprising a plurality of pairs of contact points, oscillating 20 blades pivoted adjacent their centers adapted to connect the opposite contact points, a spring for holding the contact blades in the disconnected position, a lever for turning the blades to connect one set of contact 25 points or the other at will, and means to lock said lever with the blades in contact with one of the sets of contact points.
3. An electric switch comprising a frame carrying a plurality of sets of contact points 30 oppositely disposed with respect to a set of oscillating contact blades, a set of contact blades pivotally mounted adjacent their centers on an axis between the contact points, means to hold the blades normally in the 35 neutral position, a lever for turning the blades into contact with one set of contact

points or the other set at will, and latch to lock the lever with its blades in contact with a given set of contact points, and means to release said latch when the voltage of the 40 circuit drops too low.

4. An electric switch comprising a frame work supporting a plurality of sets of contact points, a set of oscillating switch blades mounted on an axis adjacent their centers 45 between the contact points and adapted to connect opposite switch points, a casing within which the switch is mounted, a latch for holding the switch blades engaged with the contact points in the running position, a 50 cover for the casing and means to release the latch when the casing is open.

5. An electric switch comprising a frame carrying a plurality of sets of contact points, oscillating contact blades mounted on an axis 55 adjacent their centers between the contact points and adapted to connect opposite sets of contact points, means to hold said blades in the neutral position, manual means for connecting said blades with opposite pairs 60 of contact points, means for locking said plates in connection with one set of contact points, means whereby the lock will be released if the voltage goes off the line, a casing within which the switch is installed, a 65 cover therefor and means for releasing the switch if the cover is opened.

In testimony whereof I have hereunto set my hand this 7th day of November A. D. 1916.

HORATIO S. TITTLE.
